UNITED STATES PATENT OFFICE

EDWARD MALLINCKRODT, JR., OF ST. LOUIS, AND HENRY V. FARR AND LAWRENCE P. HALL, OF FERGUSON, MISSOURI, ASSIGNORS TO MALLINCKRODT CHEMICAL WORKS, OF ST. LOUIS, MISSOURI, A CORPORATION OF MISSOURI

METHOD OF PACKAGING ETHER AND THE PRODUCT THEREOF

Application filed December 20, 1929. Serial No. 415,440.

This invention relates to methods of packaging, and with regard to certain more specific features, to a method of packaging ether, together with the novel package therefor.

Among the several objects of the invention may be noted the provision of a method of packaging ether whereby incipient deterioration of the ether is effectually prevented, 10 a method which is characterized by its simplicity and ease of procedure, a method of packaging ether which obviates the use of extraneous preservative substances; the provision of a package for ether adapted for use in the method described which is easily 15 and economically manufactured, and which contains an interior surface non-catalytic to the deterioration of ether. Other objects will be in part obvious and in part pointed 20 out hereinafter.

The invention accordingly comprises the elements and combinations of elements, features of construction, arrangements of parts, materials and the combination of materials 25 and the steps and sequence of steps, which will be exemplified in the following description and the application of which will be indicated in the annexed claims:

In the accompanying drawings in which 30 are illustrated several of various possible embodiments of the invention,

Fig. 1 is a vertical section of a package; and,

Fig. 2 is a vertical section of a modification of the package of Fig. 1.

Similar reference characters indicate corresponding parts throughout the several views of the drawings.

Heretofore the conventional package for 40 ether has comprised a metal can having the general shape of the package shown in the drawings. However, the shape of the can or package is of substantially no consequence in the present invention. The previously used can was composed of conventional tin plated iron formed by the conventional process, during which any tin oxide, or dross, formed on the surface of the tin was removed by conventional processes.

It is shown in the patent to Edward Mal-

linckrodt, Jr., and Henry V. Farr, No. 1,697,320, dated January 1, 1929, that the clean tin surface presented to the ether in the can described above is deleterious to the ether itself, inasmuch as the clean tin exerts a catalytic effect accelerating the decomposition of ether in the presence of air or oxygen to peroxides, and other harmful compounds. It is further shown in this patent that oxidation of the surface of the tin exposed to the ether prevents such catalytic deterioration, and, in fact, the surface so formed is inert.

We have found that bright or unoxidized aluminum exerts a catalytic effect similar to the effect of bright tin described in the above patent, in that it catalyzes and/or aids in the deterioration of the ether to peroxides and other harmful substances. It may be that the action of bright aluminum in promoting decomposition or deterioration of ether is other than catalytic, i. e. the effect may be produced by so called "coupling" or the simultaneous oxidation of aluminum and ether. In any case the invention herein described is effective independent of the theory of the chemical reaction. A film of aluminum oxide on the aluminum substantially prevents such action.

The present invention includes the formation of a package for ether so that the interior surface will comprise a surface of aluminum oxide. Aluminum oxidizes readily in an ordinary atmosphere. This fact is taken advantage of in the present invention, wherein the troublesome operation of artificially oxidizing the tin surface in the patent above identified is eliminated.

We have found that aluminum oxide, as well as certain other metallic oxides, act similarly to tin oxide, in that they are inert, and possibly even anticatalytic or inhibitive to the decomposition of ether into peroxides, acetaldehyde and like compounds which are undesirable, if the ether is to be used for anaesthetic purposes. We have further discovered the oxidized aluminum or aluminum oxide is inert or possibly may act in such an anticatalytic or inhibitive manner, whether or not the ether be packaged in an

atmosphere of air or oxygen, or in an inert atmosphere. It is thus apparent that the present invention constitutes a valuable improvement over the former processes of packaging ether.

5 Referring to Fig. 1, numeral 1, represents the container, which in the present embodiment, is formed of sheet aluminum. Numeral 3 indicates the bottom of the container, 5 the cylindrical body, 7 the neck portion, and 9 the cap. At numeral 11 is indicated the coating of aluminum oxides on the interior of the container or package 1. It is to be noted that the thickness of the coating 11 is exaggerated in the drawings for the purpose of clarity, and that the coating 11 in the actual container may be of any thickness, so long as it substantially covers the clean aluminum surface.

10 It is not always necessary that the neck portion 7 and/or the cap portion 9 be made from aluminum, inasmuch as ether in the package is not ordinarily in contact with these portions. The packaged ether comes into contact with the neck 7 and the cap 9, only when the can is agitated or the ether poured, and such exposure to these relatively small areas is ordinarily insufficient to produce any measurable decomposition.

15 20 For this reason, it has been found commercially expedient to manufacture the neck 7 from copper sheet, tin plate, or the like, and the cap 9 from lead or other soft metals. It is to be noted, however, that a maximum degree of protection may be had by making the neck 7 and cap 9, as well as the body 5 and bottom 3, from sheet aluminum.

Sheet aluminum as it usually appears in commerce has been exposed to the air for a length of time sufficient to cause the formation of sufficient oxide coating, and artificial oxidation is therefore generally unnecessary.

40 45 In Fig. 2 is illustrated a modification of the invention wherein the sheet aluminum of Fig. 1 is substituted by a sheet iron or other metallic container 13, which has its interior surface plated or otherwise covered by an aluminum surface 15, which in turn has an oxidized surface 17. The aluminum 15 may be plated on, or it may be welded or otherwise affixed to the sheet iron 13, or it may comprise a separate container of aluminum foil or the like placed within the sheet iron container 13. The object is to provide a surface of aluminum oxide for the interior surface of the can.

50 55 The process of packaging ether herein described, therefore, comprises briefly the preparation of a package having an interior surface of aluminum oxide, and introducing the ether therein.

60 65 In view of the above, it will be seen that the several objects of the invention are achieved and other advantageous results attained.

As many changes could be made in carrying out the above, without departing from the scope of the invention, it is intended that all matter contained in the above description or shown in the accompanying drawings shall be interpreted as illustrative and not in a limiting sense.

We claim:

1. The package of ether comprising a can having its interior surface substantially covered with aluminum oxide, said can containing ether. 70
2. The package of ether comprising an aluminum can, said can containing ether. 75
3. The package of ether comprising an aluminum can having its interior surface substantially covered with aluminum oxide, said can containing ether. 80
4. The package of ether comprising a metallic can having its interior surface substantially covered with aluminum oxide, said can containing ether. 85
5. The package of ether comprising a metallic can having an interior coating of aluminum, said can containing ether. 90
6. The package of ether comprising a metallic can having an interior coating of aluminum, said interior coating having a further coating of aluminum oxide, said can containing ether. 95
7. The package of ether comprising a can having its bottom and body portions substantially coated on the interior with aluminum oxide, said can containing ether. 100
8. The package of ether comprising a can having its bottom and body portions made of aluminum, said can containing ether. 105
9. The method of packaging ether which comprises forming a package with an interior coating of aluminum oxide, and introducing ether therein. 110
10. The method of packaging ether which comprises forming a package substantially of aluminum with a coating of aluminum oxide thereon, and introducing ether therein. 115
11. The method of packaging ether which comprises forming a metallic package with an interior surface of aluminum, and introducing ether therein. 120
12. The method of packaging ether which comprises forming a metallic package with an interior surface of aluminum, said aluminum having a coating of aluminum oxide, and introducing ether therein. 125
13. The method of packaging ether which comprises forming a package with bottom and body portions of aluminum, and introducing ether therein. 130
14. The method of packaging ether which comprises forming a package with bottom and body portions having an interior surface of aluminum, and introducing ether therein.
15. The method of packaging ether which comprises forming a package with bottom

and body portions of aluminum, said aluminum having an interior surface of aluminum oxide, and introducing ether therein.

16. The method of packaging ether which comprises forming a package with bottom and body portions having an interior surface of aluminum, said aluminum having an interior surface of aluminum oxide, and introducing ether therein.

10 In testimony whereof, we have signed our names to this specification.
